(57) **CLAIM**

The ornamental design for a chair, as shown and described.

DESCRIPTION

FIG. 1 is a front right perspective view of a chair showing a first embodiment of our new design;

FIG. 2 is a front view of the first embodiment of the chair shown in FIG. 1;

FIG. 3 is a rear view of the first embodiment of the chair shown in FIG. 1;

FIG. 4 is a left side view of the first embodiment of the chair shown in FIG. 1;

FIG. 5 is a right side view of the first embodiment of the chair shown in FIG. 1;

FIG. 6 is a top view of the first embodiment of the chair shown in FIG. 1;

FIG. 7 is a bottom plan view of the first embodiment of the chair shown in FIG. 1; and,

FIG. 8 is a rear bottom perspective plan view of the first embodiment of the chair shown in FIG. 1.

The broken lines are included to show features that form no part of the claimed design.
